UNITED STATES PATENT OFFICE

132,047

DESIGN FOR A SHIRT OR SIMILAR ARTICLE

Benjamin Favorman and Emanuel T. Cherin,
San Francisco, Calif.

Application January 12, 1942, Serial No. 105,149

Term of patent 7 years

To all whom it may concern:

Be it known that we, Benjamin Favorman and Emanuel T. Cherin, both citizens of the United States, residing in the city and county of San Francisco, State of California, have invented a new, original, and ornamental Design for a Shirt or Similar Article, of which the following is a specification, reference being had to the accompanying drawing, forming part thereof.

Fig. 1 is a front view of a sport shirt, showing our design;

Fig. 2 is a rear view thereof.

We claim:

The ornamental design for a shirt or similar article, substantially as shown.

BENJAMIN FAVORMAN.
EMANUEL T. CHERIN.
